UNITED STATES PATENT OFFICE.

SAMUEL NEAL McCLEAN, OF WASHINGTON, IOWA.

BREECH-LOADING AND DISCHARGE-ACTUATED FIREARM.

SPECIFICATION forming part of Letters Patent No. 749,214, dated January 12, 1904.

Application filed March 22, 1899. Serial No. 710,014. (No model.)

To all whom it may concern:

Be it known that I, SAMUEL NEAL McCLEAN, a citizen of the United States, residing at Washington, in the county of Washington and State 5 of Iowa, have invented new and useful Improvements in Breech-Loading and Discharge-Actuated Firearms, of which the following is a specification.

My invention relates to improvements in breech-loading and discharge-actuated guns, and more particularly to machine-guns, quick-firing ordnance, and battery-guns.

In machine-guns and quick-firing ordnance as heretofore constructed the use of the high-power or nitrate powders and the enormously high rate of speed firing has subjected their operating parts to a great variety of severe and destructive strains, which strains tend to render the operation of the gun dangerous, 60 uncertain, and difficult, also to shorten the life of enormously expensive guns and to materially and injuriously affect their accuracy of fire.

One object of my invention is to construct 5 a gun which shall remedy the above defects and which shall sustain the strain of firing in the line of greatest strength, distribute it correctly on every part of the arm, limit the firing strain to a small area immediately at or near the end of the barrel.

A further object is to provide a gun in which the operating parts shall be formed with their point of greatest strength at their point of greatest strain and the structural plan of whose 5 operating parts shall be such as to avoid all unnecessary and injurious strains.

One object of my invention is to construct a gas-operated gun in which certain controlling devices shall govern the action of the actuating force of the gas on the operating parts, shall prolong the operation of this force for any required time, shall determine the power or quantity of the force applied, and shall transmit, store, and utilize this force in the 5 operation of the arm.

Heavy ordnance and disappearing guns as heretofore constructed have been rendered enormously expensive and difficult of construction by reason of the high-pressure powders and enormous strains involved in firing

heavy ammunition, and the tremendous recoil of these arms due to heavy charges employed and their great weight have necessitated the construction of complex, expensive, and enormously heavy apparatus for controlling and neutralizing the effect of the recoil. The gun which I have invented remedies these difficulties by certain gas-controlling means which utilize the force of the escaping gas to overcome or reduce or neutralize the recoil of the 60 arm and utilize the same gas-controlling devices for catching, transmitting, storing, and using the force of the discharge to operate, train, elevate and depress, and generally handle the gun and to provide certain details of 65 improvement in connection with the operating parts of the discharge-actuated gun, which will be hereinafter more fully set forth.

In the accompanying drawings, which are hereby made a part of this specification, it is 70 understood that the drawings are for the purpose of illustration only, and inasmuch as the invention may be made in many forms without in the least departing from the spirit of the same I do not limit myself to the precise 75 forms shown and illustrated.

Figure 1 is a longitudinal central vertical section of the rear end of the gun, showing the bolt action and cartridges in elevation. Fig. 2 is a view of the breech-bolt and shell-extractors in elevation, its front end broken partially to show the construction of the extractor-groove. Fig. 3 is an end elevation of the breech-bolt. Fig. 4 is a plan view of the cartridge-feeding cylinder L in elevation. 80 Fig. 5 is a fragmentary sectional view showing the bolt-timing latch in elevation. Fig. 6 is a transverse vertical section on the line 6-6 of Fig. 1. Fig. 7 is a broken central vertical section of the rear end of the receiver 85 and frame, showing a modification of the trigger-action. Fig. 8 is a broken vertical central sectional view of the barrel and gas-tube. Fig. 9 is a similar view illustrating a modification of the gas-tube. Fig. 10 is a fragmentary view of the cartridge-belt, showing a transverse section of one of the cartridge-retaining cells. Fig. 11 is a view in elevation of the gun supported in a suitable frame or mount, illustrating the construction of the 90 100

gas-tube and connection and governing devices by which it operates the gun. In this figure the trigger-action is shown in broken central section and the gun-carriage is broken out and removed on its right-hand side to expose the construction of its operating parts. Fig. 12 is a plan view of the cylinders for traversing or rotating the gun-carriage. Fig. 13 is a cross-sectional view of one of the connecting-valves. Fig. 14 is a plan view in elevation illustrating the gun supported in a disappearing-carriage, the right side wall of the carriage being broken away to illustrate its construction. Fig. 15 is a plan view of a modified form of the controlling-valve. Similar letters of reference refer to similar parts throughout the specification, and for convenience of description the different parts of the same piece and of intimately correlated pieces have been designated by a common reference-letter, the exponent placed above the letter having been changed to indicate the particular feature of the part to which the letter is intended to be applied.

25 A denotes the barrel and receiver, which are preferably integrally formed from a single piece or bar of metal in order to attain certain manufacturing and military advantages in the construction of the same. The 30 outer side of the receiver is preferably formed as a round cylinder and without any projections to render its construction complex, and the inner chamber of the receiver is formed as a straight tube of sufficient length to entirely house the breech-bolt in both its forward and rear positions. The rear end of the receiver is formed with an interrupted thread to engage with a companion interrupted thread on the dust-cap B, and the forward 35 end of the receiver is provided with a series of interrupted screw-thread lugs formed to present a series of resisting lugs or faces for engagement with a companion series of lugs on the breech-bolt. This construction of the receiver enables it to be machined and practically finished without removing it from the machine, thus bringing all its parts into alignment and greatly cheapening the cost of constructing the same. The receiver is afterward 40 cut out transversely, as indicated by the dotted lines in Fig. 1 and shown in Fig. 6, to afford a path of movement for the ammunition-belt. It is also provided with a slot on its under side in which the cam-guideway A' is located. The rear part of this cam-guideway A' is parallel with the bore of the receiver and extends forward to a point a little beyond the rear end of the breech-bolt, and at this point the guideway is formed with a cam part 45 which connects it with the forward part of the guideway A', and this forward part is also formed parallel with the bore of the receiver. In order to attain certain military and mechanical advantages in the construction 50 and operation of the breech-bolt and receiver,

I have formed in the forward end of the receiver a series of interrupted screw-threads to afford the largest possible strength in the thickness of the walls of the receiver and to afford a consecutive series of lugs for resisting the recoil and to afford certain advantages in connection with the operation and locking action of the bolt.

The breech-bolt H is preferably formed as a cylinder having its rear part hollow and its forward end solid. The front end of the bolt is provided with a series of lugs which form an interrupted thread and are consecutively arranged to sustain the strain of firing by entering into combination with companion cam-lugs on the receiver. The rear part of the breech-bolt is provided with a cam-slot H' to receive and control the action of the driving-rod E. This slot H' has a straight part at its forward end to control the firing action of the gun. The forward end of the breech-bolt is provided with an extractor-seat forming an annular groove around the bolt-head, the bottom of which in longitudinal section is formed on the arc of a circle to attain certain advantages in the latching and unlatching action of the extractors.

The shell-extractor is hook-shaped and has a forward extremity for engaging with the flange of the cartridge and has at its rearward end a flange which in longitudinal section is formed on the arc of a circle for engaging with the extractor-seat to permit a limited latching movement of the extractor. The extractor is also provided with a companion spring, as shown in Fig. 2, which is adjusted to bear against the bolt-head and exert a forward and downward tension on the extractors K K'.

The firing-pin I is a bar having its forward end tapered and its rear end adapted to receive the firing-blow of the driving-rod. The movement of the firing-pin is limited by the lug H' and is resisted by the spring I'. The driving-rod F connects the breech-bolt with the gas-action and is preferably a hollow cylinder having at its rear end a driving-head E, formed with diagonally-shaped cam-lugs E' on its respective opposite sides to engage with the guideways A'. The part E also has a projecting arm which extends up into the breech-bolt through the slot H' and projects into the path of the firing-pin I. This part E is also provided with a sear-notch for engaging with the trigger D or sear D', as shown in Figs. 1 and 7. The forward end of the driving-rod F is provided with a cylinder-head F', which is formed with annular grooves to contain a suitable preparation for preventing the injurious action of the gases of discharge. The gas-tube F' is bent at its forward end, as illustrated in Fig. 8, and is provided with a screw-thread for attaching it to the gas-chamber A' opposite the opening A'. This gas-tube is provided with a retaining-plug F' at

its rearward end, against which the rearward end of the spring F^2 rests in exerting its tension against the piston-head F' .

In Fig. 9 I have shown a modification of the gas-tube F^4 in which a T connection F^5 is formed to connect with the gas-chamber A^3 and a plug F^6 is inserted into the forward end of the gas-tube in order to readily open the tube for the purpose of cleaning or applying a suitable application to prevent the corroding or injurious action of the gases of discharge. The gas-chamber A^2 , as shown in Figs. 8 and 9, is integrally formed in the end of the barrel, and the front end of the barrel is bored out to a diameter sufficient to allow the gases of discharge to escape round the projectile in such manner as will sufficiently reduce the pressure or force of the gas, and the chamber is made sufficiently long to continue for any desired length of time the pressure of the gas within the chamber and upon the operating parts. The rear end of this chamber is provided with a long taper which terminates gradually in the size of the bore of the barrel to cause a greatly-diminished and gradually-increasing power in the force of the gas exerted on the operating parts.

The frame C is formed to be attached on the under side of the receiver and is preferably formed at either its front or rear end to interlock with the receiver, and at its other end may be screwed to the receiver in any suitable manner, one of which retaining-screws is illustrated by dotted lines in Fig. 1. The rear end of the frame C is formed with a pistol-grip C', as shown in Figs. 1 and 7, and this grip is connected with the trigger-guard and may have any form required to adapt it to the grip of the hand or finger. It is provided on its forward side with a slot or chamber to receive and control the trigger-lock D ^{8} of Fig. 7. This lock D ^{8} has a limited movement and is formed with two companion shoulders, which are movable into and out of the path of the trigger D ^{2} . The frame C is chambered on its inner side to permit the action and movement of the driving-rod F and is also chambered or mortised to permit the action of the trigger D, also the modified form of the trigger D ^{2} and the sear D ^{4} . The trigger D is pivotally supported in the frame C and has a tension-spring D'. The forward end of this trigger is provided with a sear-nose to engage with the driving-rod to control the firing action by direct engagement with the sear-notch of the rod. The modified form of the trigger shown at D ^{2} , D ^{3} , and D ^{4} interposes a sear D ^{4} between the driving-rod and trigger, and the sear-nose D ^{3} is interposed between the trigger and sear to form a toggle-joint and to afford additional lifting power in disengaging the sear.

The frame C is chambered at its middle or forward part to receive, retain, and control the feeding-cylinder L, and this cylinder L is

pivotedly retained in the frame and may be formed to project up nearly into line with the bolt-chamber, in which construction the under side of the receiver would be cut out to permit the belt-feeding cylinder to be so placed in close relation with the bolt-chamber, and in such construction the cylinder L could be formed as a hollow tube having its operative connections on its inner side and ends and the driving-rod could be allowed to pass through the tube. This feeding-cylinder L, as illustrated, however, is placed in the frame beneath the driving-rod and projects at its opposite sides into the path of the ammunition-feeding belt with which it engages. The sides of the frame C are formed with flanged guideways to receive and guide the ammunition-belt, as shown in Fig. 6, and on the left-hand side of the gun this guideway is shown hinged to the frame in order to permit the ammunition-belt to be guided in any required manner in its passage into and across the path of the bolt.

The cylinder L is formed with a series of guideways, which engage with the pin F ^{7} of the driving-rod F to control the rotating feeding movement of the cylinder L. These guideways are formed with forwardly-projecting straight parts L', which are connected with each other at their rearward ends by diagonal or V-shaped cam-guides L ^{6} and L ^{7} . The V-shaped point which connects these guides with each other is formed as a cam-switch. It is pivotally attached to the cylinder and has a wedge-shaped forward end, and its rearward end is spring-actuated to cause the switch L ^{4} to lie against the sides of the track, thus compelling the pin F ^{7} to travel always in a fixed direction through these cams, the cam-guide L ^{6} being operated by the rearward travel of the driving-rod and the cam-guide L ^{7} being operated by the forward travel of the driving-rod. It is apparent that in a modified construction of the cylinder the straight part of these guides L' could be omitted, thus materially shortening the length of the cylinder and forming the guides L ^{6} and L ^{7} so that they will open into each other at both their front and rear ends. The cylinder L is also provided with lugs or arms L ^{2} for engagement with the ammunition-feeding belt.

The spring-latch A ^{4} (shown in Fig. 5) is formed to engage with a companion notch or depression in the breech-bolt and to maintain the same latched engagement with the breech-bolt until its locking and unlocking action is complete, thus affording a means for timing the locking action of the bolt.

The cartridge-belt K may be formed of any suitable material and may be either a metallic or any other necessary kind of belt. This belt retains the cartridges G by means of a cartridge-retainer N. This retainer N is riveted to the belt and is formed with companion sides or arms which conform to the shape of the cartridge. The rear end of these cartridge-

retainers N is flanged or beveled to permit the breech-bolt to pass through the retainer in feeding the ammunition to the barrel, and this flanged part of the retainer N is slotted or cut out to permit a sufficient elastic action of the retainer. The retainer is also formed with lugs N', Fig. 10, to engage with the copper bands of the projectile and to retain the ammunition in the belt. When desired, this retainer can be formed with a grooved construction on its under side to afford a path of movement for the lug H² of the breech-bolt in feeding the ammunition.

In Fig. 11 the gun is shown supported in a suitable mount or carriage for firing. This carriage may have any desired form to adapt it to the gun with which it is intended to be used. As illustrated, O designates the frame or gun-carriage, and P the base on which the carriage is rotated. O' denotes a series of slightly-conical rollers on which the carriage turns, and P' denotes the air-reservoir, which is supported in and rotated with the frame, and O³ denotes a pair of companion cylinders, which are formed on an arc of a circle and are attached to and rotated with the carriage. In this figure the gas-tube F⁴ is divided by the wall F⁸ into a front and rear chamber, the rear chamber forming an air-compressing cylinder, and the driving-rod F is provided with an air-compressing piston F¹⁰, movable in this chamber and causing the driving-rod to act as an air-compressor. In other respects the driving-rod and gas-tube are similar to that hereinbefore described, and the forward end of the gas-tube F⁴ is formed to retain and guide the piston F' and spring F². The relation of the gas-tube to the gas-chamber A² is essentially similar to that hereinbefore described, and its preferred form is shown in Figs. 8 and 9. The driving-rod F is provided with openings located in front of the piston F¹⁰ and opening into the tube in the center of the rod F to prevent the formation of an air-cushion in the forward end of the air-compressing cylinder.

The air-compressing chamber is connected with the air-reservoir P' by the pipe F¹¹, and the air-reservoir is again reconnected with the forward end of the air-compressing chamber by the pipe F¹², and the connecting part of these pipes is formed flexible to permit the elevating and depressing movement of the gun. The air-compressor is also provided with a valve F¹³, which permits a free passage of air into the chamber and prevents its exit.

In Fig. 11, S designates an air-cylinder attached to the carriage or mount for the purpose of pneumatically governing the elevating and depressing of the gun. It is formed on an arc of a circle and is provided with a piston S⁵ and piston-rod S⁴, which is also formed on a companion arc of a circle and is attached fixedly to the gun. This cylinder S is connected at its opposite ends with the

tubes S¹¹ and S¹². These tubes are suitably connected on the opposite sides of the four-way valve S¹⁰. This valve S¹⁰ is connected with the air-reservoir by the pipe P⁸, Fig. 11, and is operated by the connecting-rod and hand-wheel S⁹. A two-way valve P¹⁵ is provided in the pipe F¹² and is governed by the connecting-rod and wheel P¹⁶. The intake-pipe F¹¹, which connects the air-compressor with the air-reservoir, is provided at its lower end with a suitable check-valve P⁷ to prevent the return escape of the air from the reservoir. The air-reservoir P' is provided with a pipe P¹⁰, which connects with a four-way valve P¹¹, and this valve is governed by the connecting-rod and wheel P¹² and is suitably connected with the pipes P¹³ and P¹⁴, which pipes connect with the cylinders O³. Movable retained in the cylinders O³ are the piston-heads P⁵ and piston-rods P⁴. These rods are attached to the frame, and the construction is essentially similar to that shown in Fig. 12. In Fig. 12 one mode of attaching these cylinders to the carriage is shown, and a mode of attaching the cylinder-rods P⁴ to the base is also shown.

In Fig. 13 is illustrated a form of the two-way valve S¹⁰, showing its manner of registering with its tubes S¹¹ and S¹², together with the external openings S¹³ and S¹⁴, with which the valve registers to permit a partial escape of the air from the cylinder S through either the tube S¹¹ or S¹².

In Fig. 14 the gun is shown supported in a disappearing gun-mount or gun-carriage, and the power controlling and transmitting devices are shown in a form adapted to run the gun to battery and to withdraw the same. In this figure the base is denoted by the reference-letter P and is similar to that hereinbefore described. The carriage or mount is denoted by the reference-letter O and is supported on the base by a series of slightly-conical rollers O'. In a general way, the carriage as here illustrated differs from that hereinbefore described by being formed to adapt it to a different mode of connection with the gun and by having projecting arms on its front and rear sides to support its manner of engaging with the gun. The carriage as here presented is bifurcated at its upper side to afford space for the movement of the gun and in a general way may have any required form to adapt it to the gun with which it is intended to be used. The power controlling and actuating devices of the gun are essentially similar to that hereinbefore described, excepting that the air-cylinder S and its piston S⁵ and piston-rod S⁴ is here modified to adapt it to operate and control the battery action of the gun. As shown in this figure, the cylinders S are formed on the arc of a circle, as hereinbefore described, and are bolted to the side of the gun-carriage in such manner as to conveniently permit the piston-rod S⁴ to be pivotally attached at its upper end to the trunnions.

of the gun; and an auxiliary cylinder S^{15} is supported on the arm or bracket at the rear side of the gun-carriage to afford a similar engagement of its piston-rod S^{16} with the pistol-grip C' of the gun-frame C .

In the invention, as illustrated in Fig. 14, the power controlling devices of the gun, comprising the gas-chamber A^2 , the gas-tube F^4 , the driving-rod F , with its actuating-spring F^2 , the gas-cylinder F^4 ; and air-compression cylinder F^{14} , are essentially similar to that hereinbefore described, and the power transmitting and storing devices, comprising the air-chamber P' and the connecting-pipe F^1 , are essentially similar to that hereinbefore described, excepting that the pipe F^{11} is formed flexible throughout its entire length to permit the necessary battery movement of the gun, and the controlling devices, comprising the valves system and connecting-pipes, are here modified to attain certain advantages in the battery movement of the gun. The pipe P^8 , as here shown, connects with the air-reservoir P' and is connected by the pipes S^{17} and S^{18} with the valves S^{19} and S^{20} . These valves S^{19} and S^{20} are retained in a suitable valve-chamber, which may be either fixedly attached to or integrally formed with the frame and are duplicates of each other. They are preferably superimposed one upon another in the same cylinder or valve-chamber, the right-hand valve having an operating-stem which projects at the right-hand side of the valve-chamber and to which is attached a worm-gear and companion gear-wheel to operate the valve on the right-hand side by the action of the rod and hand-wheel S^{21} , and the left-hand valve has a similar connection on the left-hand side with the rod and hand-wheel S^{22} , and these controlling-wheels are provided with index-fingers to indicate on a suitable dial the movement of the valve. These valves S^{19} and S^{20} may have any suitable system of connecting valve-passages to adapt them to the required registering action of the valve, but are preferably shown as three-way valves, two of which ways have a common connecting or registering point. The valve-chamber S^{23} has a connective opening with the tube S^{18} and a companion connection with the tubes S^{24} and S^{25} and is also provided with registering openings S^{26} and S^{27} and on its opposite side is provided with a companion series of openings to connect with the pipes S^{17} , S^{28} , and S^{29} and with the openings S^{30} and S^{31} , and the passage-ways within the valves are formed to correctly register with these openings. The tube S^{25} connects the right-hand valve S^{19} with the forward end of the cylinder S on the right-hand side of the gun and is bifurcated or double at its forward end to allow it to connect in a similar manner with the left-hand cylinder S , which is not shown and which is formed on the opposite side of the arm in a manner identically similar to that which is

shown in Fig. 14, and the connecting-pipe S^{29} has a similar construction and connects the left-hand valve S^{20} in a similar manner with the right and left cylinders S at a point behind the head of the piston S^4 . The tube S^{24} connects the valve S^{18} with the forward end of the cylinder S^{16} , and the tube S^{28} connects the valve S^{20} with the cylinder S^{15} at a point behind the head of the piston S^{16} , the controlling of the rear end of the gun being accomplished by a single cylinder and piston.

The elevating and depressing of the gun may be controlled in a manner hereinbefore described or by any suitable form of screw adjustment, one form of which is shown in the screw and dial S^{32} , which governs the pivotal relation of the piston S^{16} with the frame C' .

In Fig. 15 I have shown a modification of the controlling-valve, which is denoted by the reference-letter S^{33} . This valve is preferably operated by a worm-gear similar to that described in connection with Fig. 14. This valve S^{33} is a single valve, and is provided with a system of connecting-passages which registers with and controls the action of all the pipes which connect with both the front and rear cylinders S . This valve S^{33} in its preferred form is a five-way valve, one of which ways is double, and all the ways are so formed that they shall register correctly with the different pipes leading to the respective opposite ends of the cylinders S , and the valve-chamber in which the valve S^{33} is located is provided with the exit-openings S^{34} and S^{35} , with which the valve-passages register to afford exit from the respective opposite ends of the cylinders S .

The operation of the gun is as follows: Supposing the breech-bolt and operating parts, as shown in Fig. 1, to be in the forward or locked position of the bolt and the cartridge to be pushed into the barrel and the part E of the driving-rod in engagement with the sear-nose of the trigger D , a pull or grip of the hand on the trigger D will operate to lift its sear-nose out of engagement with the driving-rod, thus permitting the driving-rod to traverse the straight part of the slot H' and by its terminal movement to engage the firing-pin I and force it against the cartridge to discharge the same. The projectile when it enters the chamber A^2 at the forward end of the barrel permits the gases of discharge to escape around the ball, and the beveled or funneled shape of the rear end of the chamber allows the gas to escape around the ball in a gradually-increasing quantity, thus reducing the pressure of the gas-current to a satisfactory amount before allowing the force of the gas-current to be thrown onto or against the operating parts. The projectile in its passage through the gas-chamber A^2 operates as a valve to partially close the chamber and to continue this action for any required length of time. As soon as the projectile has entered the chamber A^2 the shape of this chamber causes a gradually-in-

creasing amount of the gases of discharge to pass through the opening A^3 into the gas-tube F^4 , and when the rear end of the projectile has traveled far enough to commence passing 5 the opening A^3 the quantity of gas which escapes through the opening A^3 into the gas-tube F^4 is allowed to increase until the projectile has passed entirely across the opening A^3 , and the opening A^3 may have any desired 10 length or shape to continue, prolong, or increase the quantity of gas which passes into the gas-tube, and this construction will afford a material advantage in adapting the gas action to the operating of heavy bolt actions 15 in large guns, it being apparent that the opening A^3 may be formed for this purpose as a prolonged slot and that the opening may have a greater diameter or receiving capacity as it passes forward. After the projectile has 20 passed beyond the opening into the gas-tube the diameter of the chamber A^2 permits a large part of the gases of discharge to escape around the projectile, thus reducing the pressure of the gas-current to any desired amount, and 25 the length of the chamber A^2 causes this pressure of the gas-current on the action to be maintained for any desired length of time or until the pressure of the gases of discharge against the driving-rod F has unlocked and 30 moved the breech-bolt back to its open position. This action of the driving-rod F compresses the spring F^2 and operates the air-compressing piston F^{10} of the driving-rod, as 35 shown in Fig. 11, at the same time that it unlocks and withdraws the breech-bolt. This air-compressing action of the driving-rod transmits and stores the power of the driving-rod in a manner hereinafter described.

The operation of withdrawing and return- 40 ing of the breech-bolt is as follows: When the breech-bolt is in its forward position and the cam-lugs E' are in the forward part of the guideways A' of the receiver, the pressure of the gases of discharge against the piston on the 45 forward end of the driving-rod causes the part of the driving-rod which projects through the slot H' to traverse the straight part of this slot, thus giving to the driving-rod an initial momentum before it encounters the cam or 50 diagonal part of the slot H' . This construction greatly increases the power of the driving-rod in starting the initial extraction of the shell. A further movement of the driving-rod causes the lugs E' to traverse the 55 guides A' until the cam part of these guides elevates the part E of the driving-rod into latched engagement with the rear end of the breech-bolt, as shown in Fig. 1, and the passage of that part of the driving-rod which 60 projects through the slot H' in the breech-bolt causes the breech-bolt to be turned or rotated until its locking-lugs H^2 have been disengaged from their companion locking-lugs A^2 of the receiver, when the further backward movement of the driving-rod causes the bolt to be 65

withdrawn to open position, at which time the modification of the trigger action shown in Fig. 7 will permit the sear D^4 to engage with the driving-rod and retain it in its rear position, thus allowing the weapon to be used as a single-loader. A pull of the hand on this trigger D^2 will operate to release the sear D^4 from the driving-rod, and the latched engagement of the driving-rod with the breech-bolt is maintained by the movement of the lugs E' through the rear part of the guides A' until the lugs E' have reached the position shown in Fig. 1 and have engaged the cam part of these guideways A' , the breech-bolt being at that time in its forward position and its locking-lugs H^2 80 being in proper relation with the locking-lugs A^2 of the receiver. The action of the beveled shape of the rear end of the breech-bolt, as shown in Figs. 1 and 2, and the action of the cam part of the guides A' causes the driving-rod to drop down out of latched engagement with the bolt, and the passage of the projecting arm of the driving-rod in and through the cam part of the slot H' causes the breech-bolt 85 to roll to its locked position and brings the driving-rod into engagement with the firing-pin, as hereinbefore described. The bolt-timing latch A^4 is spring-pressed and is provided with a conical point, which engages with a companion conical depression or V -shaped groove in the breech-bolt and maintains a semi-latched condition of the breech-bolt during the latching and unlatching action of the driving-rod with the breech-bolt, thus affording 90 additional positiveness to the operation of the breech-bolt and driving-rod. The shell-extractors, as illustrated in this application, are shown supported in an annular extractor-seat, the bottom of which is formed on an arc of a circle, and this construction permits a sort of 95 hinged relation of the extractor with the breech-bolt and allows the extractor to be held positively and steadily by the extractor-seat during the necessary movement of the extractor to permit it to engage with the flange of the shell and to cause it to lock positively with the shell in the process of extracting the same. The extractors are preferably provided with a spring to maintain a yielding tension between 100 the extractor and the seat in which it turns. 105 This method of attaching or hinging the extractor to the breech-bolt remedies the difficulties and uncertainty in the action of the extractor which exists in other methods of forming the extractor and attaching it to the bolt. 110 In the modification of the firing device shown in Fig. 7 the sear D^4 and toggle D^3 are introduced to afford additional elevating or disengaging power of the trigger in freeing the driving-rod to either load or fire the arm, and the trigger-lock D^8 is pivotally supported in the pistol-grip to allow it to be turned 115 against the trigger, thus locking it out of action, or to be turned to a point slightly beyond this, bringing its second shoulder into the path 120

125 130

of the trigger and permitting the partial firing movement of the same. This partial movement of the trigger raises the sear out of engagement with the driving-rod and retains it in that position until the magazine or belt has been emptied of its cartridges or until the trigger is released from the grip of the hand, thus controlling the automatic firing of the arm. The automatic firing of the arm 5 may also be controlled by holding the trigger D (shown in Fig. 1) out of engagement with the breech-bolt in a similar manner. The semi-automatic action of the arm may be controlled by any suitable construction of the 10 trigger which will permit the sear to reengage with the driving-rod after each successive pull of the trigger. In the semi-automatic firing-action, as shown in Fig. 7, a complete pull of the trigger carries it out of engagement with 15 the notch D⁶ of the sear D⁴ and permits the engaging part of the trigger to drop into the deeper notch D⁷, thus allowing the sear to reengage with the driving-rod after each successive shot.

20 The invention may be applied to any suitable form of magazine system or of magazine-feeding system; but I have shown in Fig. 1 an ammunition-belt provided with any suitable series of cartridge-retaining cells, one 25 form of which is shown in Fig. 6. This ammunition-belt has a movement into and across the path of the breech-bolt, and this movement is interrupted or controlled by a combination of the cartridge-belt with the driving-rod and breech-bolt to consecutively feed the 30 cartridges from the belt to the barrel and to withdraw and remove them. This feeding 35 action or combination between the driving-rod and the ammunition-belt is preferably 40 controlled by a system of cam-guideways, one form of which is shown in Fig. 4, and the 45 operation of the preferred form or feeding action of the belt is as follows: Supposing the 50 way F⁷ to be in the forward part of the guide-way L¹, (see Figs. 1 and 4,) the rearward 55 movement of the driving-rod causes this pin to traverse the straight part of the guide L¹ and to enter the cam part L⁶ at a time when the breech-bolt has been fully withdrawn. The 60 passage of the pin F⁷ through the part L⁶ causes a turning movement of the cylinder L, and the engagement of the lugs L² with the 65 slots M¹ of the cartridge-belt causes the belt to roll the cartridge partially into the path 70 of the breech-bolt. The terminal rearward movement of the driving-rod F carries the pin F⁷ past the point of the spring-pressed latch L⁴, and the tension of the spring L⁵ on this latch causes it to drop back against the side 75 of the cam-guide L⁶ and to open the guide L¹ to the return or forward movement of the pin F⁷. The initial forward movement of the driving-rod causes the pin F⁷ to traverse the cam-guide L⁶ and in so doing completes the 80 feeding movement of the cartridge-belt,

bringing the cartridge into line with the bore of the barrel at a time when the breech-bolt has been advanced far enough to bring its forward end and the shell-extractors into proper relation with the flange of the cartridge. The 70 passage of the pin F⁷ past the latch L⁴ at the forward end of the groove L⁶ causes this latch L⁴ to be swung out of the path of the pin F⁷ and to close in behind the pin F⁷, the switch L⁴ thus operating to open and close the cam-guideway L⁷, and the action of these cam-guideways L⁶ and L⁷, together with the cam-latches L⁴, thus operating to cause an interrupted rolling movement of the cylinder L and a resulting interrupting feeding movement of the cartridge-belt. 75

The operation of utilizing the forces of the discharge to handle and generally manipulate the arm is as follows: The air-compressing cylinder F¹⁴ and the piston F¹⁰, Fig. 11, utilize the direct power of the gas through the medium of the driving-rod to store some of the energy of the gases of discharge at the same time that the driving-rod operates the bolt-action. When the driving-rod, actuated 90 by the force of the discharge, travels back in the gas-tube F⁴, it causes the piston F¹⁰ to force the air out of the air-compressing cylinder F¹⁴ into and through the connecting-pipe F¹¹, causing the air to be forced past the check-valve P⁷ into the air-reservoir P'. The check-valve P⁷ permits the air to pass freely into the reservoir P' and prevents its return passage, the action of the air-compressing cylinder F¹⁴ and piston F¹⁰ thus causing the driving-rod F 95 to store a part of the energy of discharge in the air-reservoir P' by each successive discharge of the arm. During the rearward movement of the piston F¹⁰ the check-valve F¹³ prevents the escape of air from the air-compressing cylinder F¹⁴, except through pipe F¹¹, and on the reverse movement of the parts it opens and permits a sufficient quantity of air to pass in and fill the cylinder F¹⁴. During the forward movement of this piston F¹⁰ 100 the air is permitted to escape from the forward end of the cylinder F¹⁴ through the pipe F¹², and the three-way valve P¹⁵, which is attached to this pipe, is turned in such manner as to permit the air to escape through the 105 valve P¹⁵ freely into the air. This pipe F¹² also operates as a return connection between the forward end of the air-compressing cylinder F¹⁴ and the air-reservoir P', and the valve P¹⁵ being a three-way valve may be turned so 110 as to close its external opening and cause the valve to open a continuous passage from the air-reservoir P' through the pipe F¹² to the forward end of the air-compressing chamber F¹⁴, thus allowing the returned force of the 115 compressed air to withdraw the breech-bolt and set the driving-spring F² for the purpose of charging the arm or to accomplish the primary loading of the arm, after which the valve may be turned back to its original position 120

and will then register with and form an external opening for the pipe F^{12} . It is also apparent that suitable circular openings in the driving-rod F (see Fig. 11) may be formed to prevent the formation of an air-cushion in the air-compressing cylinder F^4 .

The operation of the gun elevating and depressing device for utilizing the force of the discharge to elevate and depress the arm is as follows: The pipe P^8 opens into the air-reservoir P' and permits the compressed air to pass up into the valve S^{10} , and this valve S^{10} may be any suitable form of valve, which may be turned to consecutively and either partially or entirely register with the pipes S^{11} and S^{12} , which connects it with the respective opposite ends of the pneumatic cylinder S . In order to cause the valve S^{10} to move the piston S^5 in either direction and to stop and lock it in an air-pressure at any point of its movement in the cylinder S , I have shown in Fig. 13 a form of two-way valve, which is preferably housed in a valve-chamber having five openings. The ways in this valve S^{10} are preferably formed larger than the openings with which they register, and the external openings with which the valve registers, S^{13} and S^{14} , are preferably formed smaller than the other openings.

When it is desired to elevate the gun, the operation is as follows: The valve S^{10} is turned until one of its two ways shall register with the pipes P^8 and S^{12} , thus forming a continuous passage for the escape of the air from the air-reservoir into the rear end of the cylinder S , exerting a powerful air-pressure against the rear side of the piston S^5 . The other way in the valve at this time registers with the pipe S^{11} and with the small external opening S^{13} , thus permitting a small amount of air to escape slowly or rapidly, as may be desired, from the forward end of the cylinder S through the pipe S^{11} and external opening S^{13} , and it is apparent that the valve S^{10} may be turned, so as to either partially or entirely register with the opening S^{13} or may be so turned as to close this opening S^{13} entirely, thus allowing the piston S^5 to be gradually forced forward and the gun elevated to any required aim and to pneumatically lock it there when the valve is turned far enough to close the opening S^{13} . The valve-ways S^{10} are formed larger than the openings into the pipes S^{11} and S^{12} in order to allow the valve to be fully registered with these openings and only partially or not at all registered with the openings S^{13} and S^{14} .

When it is desired to depress the arm, the operation of the valve is exactly the reverse of that described, or the valve is turned until its other valveway registers with the opening into the pipe P^8 and with the opening into the pipe S^{11} , thus giving a direct connection of the pipe S^{11} with the air-reservoir P' , allowing the air to escape from the air-reservoir into the forward end of the pneumatic cylinder S and at the same time causing the other way of the

valve to register with the pipe S^{12} and with the opening S^{14} , making a direct external opening between the rear part of the pneumatic cylinder S , through the pipe S^{12} and opening S^{14} to the air, and permitting the force of the compressed air to move the piston S^5 back to any required point at which time it may be pneumatically locked by turning the valve in such manner as to close the opening S^{14} . This valve S^{10} is controlled by the valve-rod and knurled wheel S^9 and may be provided with a suitable dial and finger or with suitable stops to govern its movement in either direction.

The carriage rotating or traversing is controlled by the valve P^{11} , and this valve P^{11} may be a two-way valve, similar to that shown in Fig. 13, or it may be any form of valve which will consecutively and alternately register with or connect the pipes P^{13} and P^{14} alternately with the pipe P^{10} and with the exit-opening of the valve, when the valve P^{11} is turned so as to cause the pipe P^{13} to register with the pipe P^{10} , making a continuous passage from the air-chamber P' to the left-hand cylinder O^3 . The air-current is in this manner permitted to pass through the pipe P^{13} into the cylinder O^3 and the piston-head P^5 , and the piston-rod P^4 being fixedly attached to the base P and the cylinder O^3 being fixedly attached to the gun-carriage the passage of the air into the left-hand chamber O^3 causes the gun-carriage to swing round to any desired point. During this time the valve P^{11} connects the pipe P^{14} with an external opening which permits the air to escape from the right-hand side of the cylinder in a sufficient quantity to allow the necessary turning movement of the gun-carriage. The reverse turning movement of the valve P^{11} swings the carriage in an opposite direction by forming a connection of the pipe P^{14} with the air-reservoir P' and causing the pipe P^{13} to register with the external opening in the valve, thus permitting the passage of air through the valve P^{14} into the right-hand cylinder O^3 , and the exit of the air from the opposite cylinder causes and permits the gun-carriage to be swung round in the reverse direction.

In that form of the invention shown in Fig. 14 the operation of the power-controlling, power-transmitting, and power-storing devices is essentially similar to that hereinbefore described—that is to say, that the action of the gas-chamber, gas-tube, driving-rod, driving-spring, air-compressing cylinder, and bolt-action is identically similar to that hereinbefore described, and so, also, is the operation of the transmitting-tube F^4 and air-reservoir P' . The operation of the pneumatic cylinders S and S^5 differs from the operation of the pneumatic cylinders hereinbefore described by being attached to the carriage and gun in such manner as to control the battery action of the arm by means of a power-transmitting device which connects these cylinders with the air-

reservoir P'. It is apparent that any suitable system of valve connection which will afford a free passage of the compressed air from the air-reservoir P' into the forward end of the pneumatic cylinders S and S¹⁵ will operate through the action of the pistons S⁴ and S¹⁶ to raise the gun to its battery position, and it is also apparent that the gun may be withdrawn from its battery position by any suitable system of valve connection which will transmit the force of the air-reservoir P' into the air-cylinders S and S⁵ behind the piston-heads S⁴ and S¹⁶ providing that an exit is afforded to the air in the forward part of the pneumatic cylinders. As shown in Fig. 14, however, the operation of the pneumatic cylinders S and S¹⁵ is controlled by a right-hand three-way valve, which controls the passage of the air from the air-reservoir to the forward end of the pneumatic cylinders and a left-hand three-way valve, which controls the passage of the air from the air-reservoir P' to the rear side of the pistons S⁴ and S¹⁶, and these valves operate to alternately open and close these connections and to provide the necessary external escape for the air-pressure.

The lifting of the gun to its battery position is controlled by the right-hand valve, and this valve is operated by the hand-wheel 30 S²¹. This hand-wheel S²¹ is connected with the valve by a worm-screw, which is similar to that shown in Fig. 15, and by means of which the valve is rolled through its connection with the hand-wheel S²¹. When this 35 right-hand valve is turned to the position shown in Fig. 14, its double valveway connects the pipes S²⁴ and S²⁵ with the pipe S¹⁸, thus forming a direct passage from the air-reservoir into the forward end of the pneumatic cylinders S and S¹⁵, and it is apparent that if the left-hand valve, which is governed by the hand-wheel S²² and a similar worm-screw connection, is turned until its valveways shall partially register with the external openings S²⁹ and S³⁰ a gradual escape of the air from behind the cylinders will cause the gun to raise to its battery position, and by opening or closing these valves it may be stopped and held in a pneumatic lock at any intermediate point of its movement. It is also apparent that the reverse of these valves, causing the right-hand valve to register with its external openings or partially register with the same and the left-hand valve to register 50 with the pipes which connect with the air-reservoir P', will effect a movement of the pneumatic pistons S⁴ and S¹⁶ in the opposite direction and will depress the arm. In this Fig. 14 I have also shown an ordinary form of screw 55 S³² for controlling the elevation and depression of the arm.

The operation of the sixway valve (shown in Fig. 15) for controlling both sets of the pneumatic cylinders by means of a single valve 60 is as follows: When the valve is in the posi-

tion shown in Fig. 15, it connects with the air-reservoir by registering with the pipes S¹⁷ and S¹⁸ and connecting them with the pipes S²⁴ and S²⁵, which lead to the forward end of the pneumatic cylinders, thus controlling the raising 70 of the gun to battery at a time when the pipes S²⁸ and S²⁹, which connect with the rear end of the pneumatic cylinders, are registered or partially registered with the external openings S³⁴ and S³⁵. The reverse movement of the 75 pneumatic cylinders is effected by turning the central or double valveway into connection with the pipe S¹⁸, thus causing this pipe S¹⁸ to connect the pipes S²⁸ and S²⁹ with the air-reservoir P' and causing the pipes S²⁴ and S²⁵ to 80 either partially or entirely register with the openings S³⁴ and S³⁵, thus admitting the air behind the piston-heads in the cylinders S and S¹⁵ and withdrawing the arm from its battery position. The pin-and-slot relation of the pin 85 S³⁷ limits the movement of this valve to give the necessary travel.

Having now fully described my invention and its mode of operation, what I claim as my invention, and desire to secure by Letters 90 Patent, is as follows:

1. In a gun, the combination with a barrel and a receiver integral therewith, of a breech-bolt, a driving-rod directly actuated by the gases of explosion, and a cam-guide for the 95 driving-rod, said guide controlling the operative relations between the bolt and driving-rod.

2. In a gun, the combination with a barrel and a receiver, of a breech-bolt having abutments thereon, and revoluble on its longitudinal axis to engage corresponding abutments in the receiver, a cartridge-belt passing transversely through the receiver, actuating devices therefor, and a driving-rod in operative 105 relation with said breech-bolt and with said actuating devices.

3. In a gun, the combination with a barrel and a receiver, of a breech-bolt having interrupted screw-threads engaging correspondingly-interrupted screw-threads in the receiver, a cartridge-belt passing transversely through the receiver, a cam-cylinder in operative engagement with said belt and actuating devices for said bolt and cylinder. 110

4. In a gun, the combination with a barrel and a receiver integral therewith, of a cylindrical breech-bolt having interrupted screw-threads engaging correspondingly-interrupted screw-threads in the receiver, a cartridge-belt passing transversely through the receiver, actuating devices therefor, and a driving-rod in operative relation with the breech-bolt, and with said actuating devices. 120

5. In a gun, the combination of the receiver 125 having the cam-guideway, the breech-bolt having interrupted screw-threads engaging correspondingly-interrupted threads in the receiver and having a hollow cylindrical portion containing the firing-pin, said cylinder 130

- having a cam-slot with a straight portion, with a driving-rod, having a lug engaging said guideway and an arm, or lug, engaging said cam-slot.
- 5 6. In a gas-operated gun, the combination of a gas-chamber at or near the muzzle of the barrel, and having an opening therein, with a gas tube or cylinder having screw-threaded connection with said opening.
- 10 7. In a gas-operated gun, the combination of a forwardly-expanding gas-chamber, with a gas tube or cylinder connected to said chamber, a piston in said tube or cylinder, and a removable plug in said tube or cylinder in advance of the forward position of said piston.
- 15 8. The combination of the air-compressor, with discharge-actuated means operatively connected to said compressor, and a graduating device controlling the application of power to said means upon the discharge of the gun.
- 20 9. The combination of the air-reservoir and compressor, with discharge-actuated means operatively connected to said compressor, a graduating device controlling the application of power to said means upon the discharge of the gun.
- 25 10. The combination of the breech mechanism and the air-compressor, with means moved by the gases of explosion to operate said breech mechanism and compressor.
- 30 11. The combination of the breech mechanism and the air-compressor, with discharge-actuated means operatively connected to said breech mechanism and compressor, and a graduating device controlling the application of power to said means upon the discharge of the gun.
- 35 12. The combination of the breech mechanism and air-compressor, with gas-actuated means connected to said breech mechanism and compressor, and a graduating device controlling the application of power to said means upon the discharge of the gun.
- 40 13. The combination of the breech mechanism and air-compressor, with a gas-tube open to the gases of explosion, a piston playing in said gas-tube, and connections between said piston and compressor, and between said piston and breech mechanism for simultaneously operating the compressor and the breech mechanism by the gases of explosion.
- 45 14. The combination of the breech mechanism and air-compressor, with the gas-tube open to the gases of explosion, devices graduating the tension of said gases therein, the driving-rod having a piston playing in said tube, and operative connections between said rod and the breech mechanism and the compressor.
- 50 15. The combination of the breech mechanism, air-compressor, and reservoir, with the gas-chamber, the gas tube or cylinder communicating therewith, the driving-rod having a piston playing in said tube or cylinder, and operative connections between said rod and the breech mechanism and the compressor.
- 55 16. The combination of the air-reservoir, compressor, and breech mechanism, with discharge-actuated means operatively connected to said compressor and breech mechanism, power-actuated elevating, depressing and training devices, and valve-controlled connections between said devices and the reservoir.
- 60 17. The combination of the air-reservoir, compressor, and breech mechanism, with discharge-actuated means operatively connected to said compressor and breech mechanism, a motor for operating the gun, and valve-controlled connections between the reservoir and motor.
- 65 18. As a means of elevating and depressing a gun, a cylinder with its piston and rod formed in the arc of a circle, one element being attached to the gun and the other to the carriage, in combination with an air-reservoir and compressor, discharge-actuated means operatively connected to said compressor and a valve-controlled passage between the reservoir and said cylinder.
- 70 19. In a gun, the combination of a receiver, the breech mechanism, and ammunition-belt passing transversely through the receiver, a feed-cylinder operatively engaging said belt, reversely-inclined cams on said cylinder, and terminating at their forward ends in a straight cam-groove, and a driving-rod engaging and operating the breech mechanism and said cylinder.
- 75 20. The combination of the ammunition-belt with a feed-cylinder having positive feed-ing engagement with the belt, a series of longitudinal parallel grooves on the cylinder, each groove being connected to its adjoining groove in either side by cam-grooves and converging to a point between said longitudinal grooves, spring-switches at the points where said cam-grooves meet each other and where they unite with the longitudinal grooves, and a driving-rod having a part engaging in said grooves.
- 80 21. The combination of a driving-rod and an ammunition-belt, with a feed-cylinder having reversely-inclined cam-faces thereon, with means on the driving-rod alternately operating on the cam-faces to shift the cylinder and engaging and holding the cylinder in its shifted position.
- 85 22. The combination of a driving-rod, a feed-cylinder normally held against revolution by said rod, an ammunition-belt operatively engaged by said cylinder, reversely-inclined cam-faces on said cylinder, cam-switches between said faces and a part on the driving-rod engaging said cam faces and switches upon the reciprocation of the rod.
- 90 23. The combination of a breech-bolt having an extractor-seat formed in longitudinal section on the arc of a circle, an extractor

having correspondingly-formed flanges engaging said seat so as to turn thereon, a spring-latch located in the receiver and engaging said breech-bolt with a yielding tension, a driving-rod and reacting spring therefor and connections between the rod and bolt.

24. The combination of the gun, the breech-block, a gun-carriage, and the air-reservoir mounted thereon, with an air-compressor connected to such reservoir and discharge-actuated means operatively connected to the breech mechanism and to the compressor.

25. The combination of the gun, the gun-carriage, the air-reservoir carried thereby, the elevating and depressing cylinders formed in an arc of a circle, the pistons of like form moving in said cylinders, one of said parts being attached to the carriage and the other to the gun, and connections between the reservoir and cylinders.

26. The combination of the gun, the compressor, the gun-carriage, the air-reservoir supported thereon, connections between the compressor and the reservoir, the arc-shaped elevating and depressing cylinders with their pistons, one of which is attached to the gun and the other to the carriage, and connections between said cylinders and the air-reservoir.

27. The combination of a transversely-slotted receiver, a cartridge-belt, and means intermittently moving said belt through the receiver and locking said belt against movement in the intervening intervals.

28. The combination of the gun, the gas-chamber, the gas-cylinder connected thereto, the driving-rod having a piston playing in said cylinder against the tension of a spring, an air-cylinder, a piston on said driving-rod playing in said air-cylinder, the breech-bolt directly connected to said driving-rod, and the cartridge-belt-actuating cylinder directly operated by said rod.

29. The combination of a gun, the double-acting piston in the cylinder under the gun-barrel actuated in one direction by the gases of explosion and in the reversed direction by a spring, a second piston connected to the first piston by a suitable rod and playing in an air-compressor cylinder, the air-reservoir connected to the last-mentioned cylinder and the breech mechanism of the gun operatively connected to the gas-actuated piston.

30. The combination of a gun-barrel, its

breech mechanism, a gas-cylinder connected to the gun, connections between said cylinder and the gun-barrel, means permitting a gradually-increased pressure of the gases of explosion to pass from the gun-barrel to the cylinder upon the discharge of the weapon, a piston in said cylinder and direct connections between said piston and the breech mechanism.

31. In a gun, the combination of the gun-barrel, having a gas-chamber formed near the muzzle end thereof, a receiver, a cylindrical breech-block playing in said receiver, a gas-tube connected to said chamber, a piston in said tube, a driving-rod connected to said piston and operatively engaging the breech-block, a cartridge-belt having intermittent movement through the receiver in the path of the block, a feed-cylinder for said belt and means on the driving-rod alternately shifting said feed-cylinder and locking it against movement.

32. In a gun, the combination of breech mechanism, means actuated by the gases of explosion for operating said breech mechanism with means graduating the force with which the gases of explosion are applied to said means.

33. The combination of a breech-block, and the intermittently-moving cartridge-belt with means actuated directly by the gases of explosion for intermittently operating said belt and bolt and locking the belt against movement during the intervening intervals.

34. The combination with a gun and its mount, with means operated upon the discharge of the gun to store power, means whereby a portion of said power may be applied to train the gun, and means whereby a portion thereof may be applied to elevate and depress the gun.

35. The combination of the breech-block, the gas-operated driving-rod, a cartridge-belt operatively connected to said rod, and the pivoted guide for said belt.

36. The combination of a breech-block and the extractor, rocking on the front end thereof, the seat therefor being a portion of a sphere.
